Patented Jan. 6, 1976

238,343

BICYCLE WHEEL REFLECTOR

Peter M. Hamborg, 547 Princeton Drive,
Costa Mesa, Calif. 92626

Filed July 12, 1974, Ser. No. 487,867

Term of patent 14 years

Int. Cl. D10—06

U.S. CL. D10—111

FIG. 1

FIG. 5

FIG. 4

FIG. 1 is a front perspective view of a bicycle wheel reflector showing my new design;

FIG. 2 is a rear elevational view thereof on a reduced scale;

FIG. 3 is a bottom plan view thereof;

FIG. 4 is a greatly enlarged cross-sectional view taken on line 4—4 of FIG. 2; and

FIG. 5 is a cross-sectional view taken on line 5—5 of FIG. 4.

The wheel and second reflector in FIG. 1 and spokes in FIGS. 2, 3 and 4 are shown in broken lines for illustration purposes only.

I claim:

The ornamental design for a bicycle wheel reflector, substantially as shown and described.
